US00D573372S

(12) **United States Design Patent**
Gibbs et al.

(10) **Patent No.:** US D573,372 S
(45) **Date of Patent:** ** Jul. 22, 2008

(54) **MODULAR FURNITURE**

(75) Inventors: **Kenneth S Gibbs**, Baldwin, MI (US);
David Field, Holland, MI (US); **Michael Wiersema**, Holland, MI (US)

(73) Assignee: **The Brill Company**, Ludington, MI (US)

(**) Term: **14 Years**

(21) Appl. No.: **29/278,110**

(22) Filed: **Mar. 20, 2007**

(51) **LOC (8) Cl.** 06-04

(52) **U.S. Cl.** D6/477

(58) **Field of Classification Search** D6/477-479,
D6/396, 449, 451, 473-474; 108/1, 59, 92,
108/161, 166, 186, 192; 211/90, 186-188

See application file for complete search history.

(57) **CLAIM**

The ornamental design for the modular furniture, as shown and described.

DESCRIPTION

FIG. 1 is an oblique view of one embodiment of the invention; FIG. 2 is a front elevation view of the invention shown in FIG. 1;

FIG. 3 is a side elevation view of the invention shown in FIG. 1, the opposite side being a mirror image of FIG. 3;

FIG. 4 is a rear elevation view of the invention shown in FIG. 1;

FIG. 5 is a top view of the invention shown in FIG. 1;

FIG. 6 is a bottom view of the invention shown in FIG. 1;

FIG. 7 is another oblique view of the invention shown in FIG. 1;

FIG. 8 is an oblique view of an alternate embodiment of the invention;

FIG. 9 is a front elevation view of the invention shown in FIG. 8;

FIG. 10 is a side elevation view of the invention shown in FIG. 8, the opposite side view being a mirror image of FIG. 10;

FIG. 11 is a rear elevation view of the invention shown in FIG. 8;

FIG. 12 is a top view of the invention shown in FIG. 8; and,

FIG. 13 is a bottom view of the invention shown in FIG. 8.

The broken lines in the drawings are for environmental purposes only and form no part of the claimed design.
